[57] **CLAIM**

The ornamental design for the laser beacon, as shown and described.

DESCRIPTION

FIG. 1 is a top front right side perspective view of a laser beacon illustrating our design;

FIG. 2 is a top plan view thereof;

FIG. 3 is a bottom plan view thereof;

FIG. 4 is a front elevational view thereof;

FIG. 5 is a right side elevational view thereof;

FIG. 6 is a rear elevational view thereof;

FIG. 7 is a left side elevational view thereof;

FIG. 8 is a top front right side perspective of an alternative embodiment of a laser beacon illustrating our design; and,

FIG. 9 is a top plan view of the embodiment in FIG. 8, the remaining views of the embodiment in FIG. 8 being identical with the embodiment in FIGS. 1-7.

FIG. 1

FIG. 2

FIG. 3

FIG. 4

FIG. 5

FIG. 8

FIG. 9
